UNITED STATES PATENT OFFICE.

FRANKLIN E. ARNDT, OF GALION, OHIO, ASSIGNOR TO THE GALION IRON WORKS & MANUFACTURING COMPANY, OF GALION, OHIO, A CORPORATION OF OHIO.

ROAD-MACHINE.

1,190,365.

Specification of Letters Patent. Patented July 11, 1916.

Application filed February 28, 1914. Serial No. 821,764.

To all whom it may concern:

Be it known that I, FRANKLIN E. ARNDT, a citizen of the United States, residing at Galion, in the county of Crawford and State of Ohio, have invented certain new and useful Improvements in Road-Machines, of which the following is a specification.

This invention comprehends certain new and useful improvements in reversible road machines or graders and relates particularly to the operating means for what is known in the art as a circle, which is suspended by the draw bars of the machine and which in turn supports the mold board and blade, the circle being mounted for a rotary movement whereby the blade may be "reversed" and held at any desired angle to the line of draft.

The present invention has for its primary object a simple, strong, durable and efficient construction and arrangement of parts whereby the circle may be easily turned as required through the instrumentality of a flexible shaft under the control of the operator on the platform of the machine.

With this and other objects in view, as will more fully appear as the description proceeds, the invention consists in certain constructions, arrangements and combinations of the parts that I shall hereinafter more fully describe and claim.

For a full understanding of the invention, reference is to be had to the following description and accompanying drawing, in which—

Figure 1 is a plan view illustrating conventionally certain parts of a road machine in full and dotted lines and showing my invention embodied therein. Fig. 2 is a plan view of the circle itself, but with the bolts omitted. Fig. 3 is an enlarged transverse section on the line 3—3 of Fig. 2.

Corresponding and like parts are referred to in the following description and designated in all of the views of the accompanying drawing, by like reference characters.

Referring to the drawing, the numeral 1 designates the side bars or sills of the wheeled framework of a road machine, 2 designates the draw bars which are suspended by the framework, 3 designates the platform upon which the operator stands to control and adjust the machine, and 4 designates as a whole the rotatably mounted circle the operating mechanism for which

forms the subject matter of the present invention.

The circle 4 includes a body ring 5 of angle metal, as clearly illustrated in Fig. 3, said body ring being formed in two semi-circular sections arranged with their ends in abutting relation to each other. These sections are joined together by a curved splice bar 6 bolted thereto and also by the upper edge of the bracket knees 7 to which the mold board 8 is attached.

Malleable segments 9, having recessed upper faces 10, are set in under the outwardly projecting and relatively horizontal flange of the body ring 5, there being four of these segments in the present instance, arranged in abutting relation to each other at their ends to form a complete ring, although it is to be understood that the invention is not limited to this number. These segments 9 project outwardly beyond the outer edge of the body ring 5 and flush with the upper surface thereof, as clearly illustrated in Fig. 3 and are secured to the outwardly projecting flange of said ring by bolts 11 or similar fastening devices. In the preferred construction and arrangements of the parts, there are four bolts for each segment, the bolts being arranged in pairs, one pair at about the middle of each segment and the other two at the ends thereof, the parts being so arranged that two pairs of these bolts will be positioned on opposite sides of the joints between the two sections of the body ring 5 whereby the segments and their fastening devices will assist in holding the two sections of the body ring together.

The outer edges of the segments 9 are toothed, as indicated at 12, for engagement by a worm 13 which is carried by a transversely extending shaft 14 journaled in a casting 15 which not only serves as a support for the shaft, but as a brace for the draw bars 2. The shaft 14 is provided at one end with a bevel pinion 15 which meshes with a corresponding pinion 16 on a flexible operating shaft 17, said shaft being formed in two sections connected by a universal joint 18 and the rearmost section extending upwardly and rearwardly toward and above the platform 3, where it is provided at its rear end with a hand wheel 19 whereby it may be easily operated. The foremost section of the flexible operating shaft 17 ex-

tends through and is supported by an apertured bracket 20, secured to one of the sills or side bars 1 of the framework, this bracket being secured to the sill on the side thereof which is opposite to the casting 15 and the shaft 14 extending through said bracket 20, whereby an additional bearing support for the shaft 14 is provided.

From the foregoing description in connection with the accompanying drawing, the operation and advantages of my improved circle and operating means therefor will be apparent. In the practical use of the device, the operator standing on the platform 3, may easily adjust the mold board and its blade by turning the flexible operating shaft 17 in one direction or the reverse, the motion being transmitted from said shaft through the bevel pinions 16 and 15 and through the shaft 14, worm 13 and the circle 4. It will also be seen that the circle itself is of very simple, durable and strong construction. The splice bars and body ring sections may be easily made of wrought steel and the segments of malleable steel, and the parts may be very readily secured together in assembled relation to form the complete circle.

While the accompanying drawing illustrates what I believe to be the preferred embodiment of my invention, it is to be understood that the invention is not limited thereto but that various changes may be made in

the construction, arrangements and proportions of the parts without departing from the scope of the invention as defined in the appended claim.

What I claim, is:

In a road machine, the combination with the draw bars thereof and a revoluble circle supported thereby, said circle being provided with a toothed rack, of a brace secured to said draw bars and extending transversely from one draw bar to the other, a transverse shaft journaled in said brace and provided intermediate of its ends with a worm meshing with said rack between said draw bars, the shaft being provided at one end outside of the adjacent draw bar with a bevel pinion, a sectional flexible operating shaft extending longitudinally of the machine toward the rear thereof outside of the draw bars, a pinion on the forward end of said flexible operating shaft meshing with the first-named pinion, and a bracket secured to the outer side of one of said draw bars, the transverse shaft and the foremost section of the operating shaft extending through and having bearings in said bracket.

In testimony whereof I affix my signature in presence of two witnesses.

FRANKLIN E. ARNDT.
